Des. 233,584
Patented Nov. 12, 1974

233,584

COMBINED CONDIMENT SET AND TRAY THEREFOR

Augusto Salviato, Corso Mario Abbiate 110,
Vercelli, Italy

Filed July 23, 1973, Ser. No. 382,098

Claims priority, application Italy Apr. 30, 1973

Term of patent 14 years

Int. Cl. D7—06

U.S. Cl. D7—55

FIG. 1

FIG. 2

FIG. 1 is a top perspective view of a combined condiment set and tray therefor showing my new design;
 FIG. 2 is a side perspective view thereof;
 FIG. 3 is an end perspective view thereof;

FIG. 4 is a top plan view thereof with the cruets being omitted for purposes of illustration; and

FIG. 5 is a bottom plan view thereof.

I claim:

The ornamental design for a combined condiment set and tray therefor, as shown and described.
